HOT TOPS FOR INGOT MOLDS

Claude Marie and René Thierry, Corbeil-Essonnes, France, assignors to Societe a Responsabilite Limitee Doittau Produits Metallurgie, Corbeil-Essonnes, France, a corporation of France

Filed Mar. 3, 1961, Ser. No. 93,102

Claims priority, application France Mar. 7, 1960
3 Claims. (Cl. 22—147)

Various types of hot tops for ingot molds are known which are positioned at the upper end of the ingot mold and are intended to receive a certain amount of molten metal forming a deadhead or runner which feeds the core of the ingot during its solidification. In order to allow the use of the ingot mold for ingots of different volumes, hot tops of the reentering or shiftable type are used which may be caused to sink to a variable extent into the ingot mold. Two modus operandi are then possible, to wit: either the hot top is held fast in position during the solidification of the ingot and the cooling of the ingot, so that the shrinkage is balanced only by the formation of the runner, or the hot top is allowed to float and to sink gradually inside the ingot mold during the solidification of the ingot. Now, my invention has for its object a hot top of this type which is adapted for use in accordance with either of the two techniques which have just been referred to.

Shiftable hot tops, as generally resorted to, are constituted by a peripheral metal frame provided with an inner lining of refractory material, whether heat insulating or exothermic; at the lower end of said frame are fitted, on the one hand, an annulus of refractory material and, on the other hand, and generally in registry with the plane of separation between the frame and the annulus, an element such as a thin metal blade forming a packing between the hot tops and the wall of the ingot mold, said element being adapted to initiate the solidification of the molten metal which has crept through the gap between the metal walls of the hot top and of the ingot mold respectively.

These shiftable hot tops show various drawbacks, to wit: a lengthy and costly preparation of the packing, the brittleness of the annulus at the lower end of the frame, which annulus is made of refractory material, the necessity of renewing said annulus at each casting, a delicate molding as required, in order to prevent the shocks between the annulus and the wall of the ingot mold, a substantial offset along the line of connection between the ingot mold and the runner as a consequence of the cross-section required for the refractory annulus and of the partial or complete adherence of the ring to the lower end of the runner, which adherence is increased by the burrs formed by the metal creeping through the gap between the ingot mold and the hot top, which may lead to the objectionable inclusion of refractory material, which is highly detrimental to the rolling of the ingots obtained.

My invention has for its object, while retaining and even improving the advantages inherent to the above-referred to type of hot tops to wit: the possibility of casting ingots of different weights, the cutting out of any burr, the reduction of the wear at the upper end of the ingot molds and the reduction of the losses of heat in a lateral direction to reduce or even cut out at least part of the above-mentioned drawbacks.

My invention has for its object a method for forming the packing of a hot top of the type considered after introduction of the hot top inside the ingot mold through extrusion of the bead of material having a plasticity arranged at the lower end and along the periphery of said hot top.

The hot top forming a further object of our invention

2

is constituted chiefly by a metal frame provided with a peripheral flange of which the cross-section corresponds, with the clearance required for its fitting, to that of the ingot mold and an outer hoop, of which the lower surface cooperates with the flange of said frame, so as to allow the compression of a material having a plasticity fitted between said parts, and which is driven laterally out so as to form the packing between the hot top and the ingot mold.

According to a preferred embodiment, the hoop is sufficiently heavy for its weight to ensure the compression and the extrusion of the material forming the packing and to oppose the ferrostatic thrust exerted on said packing, its own weight being added to that of the frame, so as to balance the general static thrust exerted by the molten metal. An arrangement of stops limits the vertical rising movement of the hoop with reference to the frame and hoisting means for the whole hot top system are provided on the hoop, while the frame is in its turn provided with lateral supports which allow setting it at the desired height inside the ingot mold.

The frame of the hot top may be provided with any conventional inner refractory lining, whether heat insulating or exothermic, for instance of the type described in the French Patents No. 1,084,725 of June 12, 1953, No. 1,112,520 of October 11, 1954, or No. 1,112,966 of October 21, 1954.

The material which is to form the packing may be made of any substance provided with a sufficient plasticity to allow its extrusion under the weight of the hoop or under the action of thrust-producing means inserted between the frame of the hot top and the hoop. It is possible, in particular, to resort to a siliceous, aluminous, magnesian limestone, lime-containing, carbide-containing or the like ground, or else, to refractory or melted cements, putties of the type sold in trade and various agglomerated mixtures incorporating the above-mentioned refractory products with the addition of vegetable or mineral oils, mealy or starchy products, residuary paper pulp, sugar-containing products, natural or synthetic resins, cement, sodium silicate and the like.

Said pasty material may be incorporated through direct introduction into the space which it is to occupy and which is open to its maximum between the edge of the shrinkage hole frame and the lower end of the loop, but it is also possible to introduce it in the form of elongated elements of a predetermined outline forming round, square or rectangular bars, which bars are then fitted inside the gap considered; the material may, if it is naturally too plastic to form a rigid structure, be introduced into woven or extruded sheaths made of metal, textile material, synthetic resins, asbestos or the like; the cross-section of the sheath being irrelevant.

Our invention has also for its object the plastic material adapted to form packings in accordance with the method disclosed in association with the above-described hot tops.

We will now describe an embodiment of our improved hot top, reference being had to the accompanying drawings, wherein:

FIG. 1 is a partly elevational, partly sectional view of a hot top according to the invention, as positioned before the hoop is lowered over it.

FIG. 2 is a view similar to FIG. 1 showing the arrangement after the hoop has been lowered.

In said drawings, 1 designates the upper section of the ingot mold. In the opening of the latter, there is inserted the lower end of the frame 2 of the hot top, which frame is constituted by a metal wall in the shape of the frustum of a pyramid or the like and is provided with an outer flange 3 along its lower edge, of which flange the periphery is fitted inside the opening of the ingot mold with a clearance *e* corresponding to the clearances generally allowed

for foundry work. At its upper end, the wall 2 is provided also with an outer peripheral flange 4 extending also inwardly, so as to protect the upper portion of the lining 5 of the hot top. The inner surface of the wall 2 is provided with ribs which are not illustrated and to which are secured, through gluing or otherwise, exothermic plates forming said inner lining 5, which lining does not form part of the present invention and may be of any known type whatever, so that it need not be described with any further detail.

Round the wall 2 forming the frame of the hot top, there is mounted a metal hoop 6 adapted to move vertically within a limited range. Said hoop is guided by elongated slots 7 formed therein and engaging radial arms 8 rigid with the outer wall of the hot top 2, which arms form the supports of the latter resting on carrier blocks 9 defining, at least until the casting is performed, the depth of engagement of the hot top inside the ingot mold. The hoop 5 carries furthermore lateral trunnions 10 through which it may be hoisted and lowered.

The hot top is firstly suspended through the trunnions 10 of the hoop, the frame of the hot top being held by arms 8 extending through the slots of the hoop. The inner lining of the hot top is assembled in the case of an exothermic lining, or else, it is merely checked in the case of a semi-permanent lining made of refractory bricks. There is then laid in the gap separating the upper surface of the flange 3 from the lower surface of the hoop 6, an element made of a material having a sufficient plasticity, say an edge-ring or bead 11 made of one of the above-mentioned substances and preferably, in practice, of thick silicate-containing grout or of putty.

The arrangement is then allowed to sink inside the ingot mold 1 until the arms or supports 8 rest on the carrier blocks 9, of which the height is selected in conformity with the weight of the ingot to be cast (FIG. 1); from this moment onwards, only the hoop continues sinking and its weight compresses the bead 11 and urges the material forming the latter outwardly. It constrains thus said material to enter the clearance *e* between the periphery of the flange 3 and the lower end of the hoop 6. It is apparent, from inspection of FIG. 2, that the bead material 11 provides a perfect packing and, if the volume of the bead is suitably selected, the lower edge 12 of the deformed packing extends into proximity with the lower surface of the flange 3 on the frame 2, which limits the formation of burrs to a maximum.

It is then possible to cast the metal and, after the casting, the blocks 9 are removed if the hot top is used in accordance with the procedure usually resorted to for floating or shiftable hot tops.

The above-described embodiment illustrated by way of example may be modified in many manners without unduly widening the scope of the present invention which covers generally all the ingot molds in which the packing

is formed through extrusion of a mass having plasticity. What we claim is:

1. A hot top for operation with an ingot mold, comprising a metal frame provided with an outer peripheral flange at its lower end, the cross-section of which corresponds with a clearance to the size required for it to engage the opening of the ingot mold, a hoop surrounding the frame and shiftable vertically over the latter down to a position leaving a small gap between its lower edge and the flange on the frame, and a bead in the gap between said lower edge of the hoop and the flange and adapted to be crushed and driven outwardly by the lowering of said hoop over the frame to form a packing between the latter and the opening of the ingot mold.

2. A hot top for operation with an ingot mold, comprising a metal frame provided with an outer peripheral flange at its lower end, the cross-section of which corresponds with a clearance to the size required for it to engage the opening of the ingot mold, a hoop surrounding the frame and shiftable vertically over the latter down to a position leaving a small gap between its lower edge and the flange on the frame, and a bead in the gap between said lower edge on the hoop and the flange and adapted to be crushed and driven outwardly by the lowering of said hoop over the frame to form a packing between the latter and the opening of the ingot mold, the weight of the hoop ensuring the compression and the extrusion of the material forming the bead and opposing the ferrostatic thrust exerted through the gap on the compressed bead, the added weight of the hoop and of the frame balancing the total static thrust of the molten metal in the ingot mold.

3. A hot top for operation with an ingot mold, comprising a metal frame provided with an outer peripheral flange at its lower end, the cross-section of which corresponds with a clearance to the size required for it to engage the opening of the ingot mold, a hoop surrounding the frame and shiftable vertically over the latter down to a position leaving a small gap between its lower edge and the flange on the frame, a bead in the gap between said lower edge of the hoop and the flange and adapted to be crushed and driven outwardly by the lowering of said hoop over the frame to form a packing between the latter and the opening of the ingot mold, a stop system limiting the vertical movement of the hoop with reference to the frame, outer projections on the hoop for the handling of the frame and hoop system, supporting arms outwardly rigid with the frame, and blocks laid on the ingot periphery round its opening and on which said supporting arms are adapted to rest to allow the sinking of the lower edge of the hoop into engagement with the bead.
